VARIABLE SOUND-CONVEYER OR HORN FOR TALKING-MACHINES OR THE LIKE.

1,362,919.

Specification of Letters Patent.

Patented Dec. 21, 1920.

Application filed November 21, 1917. Serial No. 203,120.

To all whom it may concern:

Be it known that I, GEORGE W. BEADLE, a citizen of the United States of America, and a resident of New Rochelle, New York, have invented a new and useful Improvement in Variable Sound-Conveyers or Horns for Talking-Machines or the like, which invention is fully set forth in the following specification.

10 This invention is intended primarily for talking-machines of the "concealed-horn" type, but may be employed with other talking-machines, and indeed as a sound-conveyer for other purposes.

15 It is an object of the invention to provide a variable horn,—that is, a horn whose discharge area and inclosed space can be varied at will. This object is accomplished by providing means for varying the geometrical 20 volume of the horn from its discharge end toward its sound-receiving end. The construction preferably, though not necessarily, includes a horn that is substantially rectangular in cross-section, with two opposite 25 sides stationary and the other two sides mounted movably, as by being hinged at their rear ends; and, preferably, the two stationary walls flare outwardly, while the movable walls are of a similar flare in shape.

30 The invention also comprises means for swinging the movable walls into the different desired adjustments, preferably simultaneously, for contracting or expanding the mouth of the horn; means for hinging the 35 movable walls slidably, so that their front edges can be moved rectilinearly; means for producing a snug fit against the stationary walls in the different positions of the movable walls; and, when installed into a talking-machine cabinet, means for concealing the open spaces at the rear or outside of the 40 movable walls.

The invention likewise comprises the combinations of some or all of the foregoing 45 features, and also the additional features hereinafter recited in the appended claims.

The invention is susceptible of expression in various physical embodiments, but will be best understood by the following description which, with the accompanying drawings, sets forth a preferred embodiment of the invention installed in the cabinet of a

"concealed-horn" talking-machine. In these drawings:

Figure 1 is a perspective of a machine containing the invention, showing the partly-expanded mouth of the horn. 55

Fig. 2 is a fragmentary vertical section, from front to rear, through Fig. 1.

Fig. 3 is a fragmentary horizontal section through the same, but showing the horn with its mouth completely contracted. 60

Fig. 4 shows an elevation of the outer side or rear of one of the two adjustable side-walls of the horn, and a perspective of the 65 adjacent flexible shield for concealing the exterior opening.

Fig. 5 is a perspective of an anchorage for the actuating-cable.

Fig. 6 is a horizontal section of a detail, 70 showing the connection between the outer edge of one of the adjustable side-walls and the adjacent actuating-means.

Fig. 7 is a fragmentary horizontal section, indicating, by broken lines, different 75 positions of the adjustable side-walls.

Referring to the drawings, in the lower part of the cabinet 1 may be the usual storage-space 2. 3 is the upper platform or deck, beneath which is located the motor (not 80 shown), whose upright main shaft 4 protrudes through said deck, and carries the turntable 5, for a disk record 6. The tone-arm 7 carries at its outer end the sound-box 8, and at its inner end is swiveled (to pivot 85 vertically) upon the elbow 9, which latter is swiveled upon the ferrule 10 (to permit the tone-arm to swing horizontally across the face of the record-disk). The ferrule 10 connects the tone-arm with the sound- 90 conveying elbow 11, from whose lower member extends the horizontal outwardly-flaring "throat" 12, whose upwardly-flaring upper wall is extended to (or near) the front of the cabinet to constitute the stationary roof 95 13 of the horn; while its lower wall is similarly extended downward to constitute the stationary floor 14 of the horn. The two side-walls of the throat diverge forwardly, and are extended, as at 15; and, if desired, 100 they may even extend all the way to the front of the cabinet. All the foregoing is a well-known structure.

If desired, the rectangular space between

the front edges of the roof and floor respectively may be partly or entirely concealed, as by a stationary grid or fabric or by a series of pivoted shutters; but, in the 5 particular embodiment here shown, a somewhat different construction is employed for that purpose.

In front of the throat 12 are located the two forwardly-extending movable side-walls 10 16 and 17, which with the roof and floor constitute the horn. They are shaped to fit vertically in the flaring space between the roof and the floor of the horn, and are hinged at their rear to the stationary extensions 15. Preferably these two movable side-walls are so connected together that they can be moved simultaneously, but in opposite directions, whereby they can be simultaneously swung together or swung 20 apart (to contract or enlarge the mouth of the horn).

Preferably these movable side-walls are so hinged as to be longitudinally slidable, in order to permit their front edges being 25 moved in rectilinear direction, and to accommodate themselves to the varying height of the vertical space occupied in their different positions of adjustment. In the preferred form, this slidable hinging consists 30 of a strap-hinge, one of whose members 18 is rigidly secured to the rear face of the side-wall, while the other hinge-member is slidably connected to the extension 15, as by a single headed-screw 19 passed through 35 the slot 20. By this arrangement, the front edge of each side-wall can be moved rectilinearly across the front of the cabinet, while the pivot-pintle 21 slides in and out, as indicated by broken lines in Fig. 7 (instead 40 of said front edge traveling on the arc of a circle, with a fixed pivot).

Preferably, means are provided for producing a snug fit between the upper and lower edges of the movable side-walls and 45 the floor and roof of the horn. In the particular structure shown, this consists of a vertically-slidable plate 22, located in a longitudinal rabbet in the rear of the upper portion of the side-wall, the outer end of 50 said plate being preferably pivoted to the front upper corner of the side-wall, as by a pivot 23, while a spring 24 tends to elevate the rear end of said slide. The upright strip 25 may be secured to the rear of the 55 side-wall, to guide the rear end of this slide-plate in vertical alinement.

If it be desired to actuate the two side-walls simultaneously, a convenient arrangement for that purpose comprises the two 60 pulleys 26-26', mounted on vertical axes at opposite sides of the cabinet, preferably near the top of the rectangular opening. An endless cable passes around these two pulleys, its two members crossing over as 65 indicated in Fig. 3; and one cable-member

27 is suitably secured to the front of the movable side-wall 16, while the other member 27' is similarly secured to the other movable side-wall 17. Any suitable device or handle, as 28, can then be employed for 70 swinging either one of said walls (or for moving the cable), whereupon the two side-walls will swing simultaneously toward or away from each other, to contract or expand the mouth of the horn. 75

Preferably, suitable means will be provided for concealing the open spaces at the outer sides or rear of the two movable side-walls when partly (or completely) contracted. In the particular form shown, a 80 part of said concealing-means constitutes likewise a part of the means for actuating the side-walls. More specifically, said concealing-means comprises two flexible shields, one on either side of the mouth of the horn 85 (as defined by the positions then occupied by its movable walls 16-17), consisting of a series of vertical splints mounted upon cloth (like the roll-top of a desk), with suitable upper and lower runways located rectilin- 90 early across the front of the cabinet and extending back behind the rear of the side-walls of the cabinet. Each of the two adjacent forward shield-members 29 and 30 is connected loosely to the front edge of their 95 respective movable side-wall. The particular connection shown comprises (see Fig. 6) a V-nosed projection 31 secured rigidly to the front of each side-wall, and extending into a somewhat more obtuse V-seat in 100 or carried by the member 29 (30), where it is yieldingly secured, as by a coiled spring 32, whose two ends are secured respectively to the member 29 (30) and to the nose 31.

The mechanical actuation is obvious. For 105 instance, by moving handle 28 to the right (of Fig. 3), this movement directly swings side-wall 16 to the right, and simultaneously draws cable-member 27 in the same direction; this latter simultaneously draws the 110 other cable-member 27' and the other side-wall 17 to the left, thereby symmetrically expanding the mouth of the horn,—while simultaneously the two flexible shields are retracted into their race-ways. Of course 115 the mouth of the horn could thereafter be contracted by moving the handle 28 in the opposite direction.

The acoustical advantages of the variable horn will also be readily appreciated. By 120 contracting its mouth suitably, the horn becomes better adapted for playing softer tones; and by expanding its mouth, for louder tones. And, in contracting its mouth, the converging side-walls do not act to choke 125 the sound-waves or produce objectionable reflexes or echoes. The variations in the shape of the horn, and in the size of its mouth, modulate the sounds emitted therefrom, without impairing their quality. 130

It will be understood that the foregoing detailed description discloses merely a preferred embodiment of the invention, and that the invention is not limited to the precise construction and arrangement here disclosed, but might be embodied in various forms; and parts of the invention can be inverted or transposed with other parts, or even omitted, and modifications in the structure and arrangement could be employed, all within the spirit of the invention.

The invention having been thus described in detail, what is claimed is:

1. The combination of a talking-machine cabinet having an opening at its front, a sound-conveyer or horn located in said cabinet and discharging toward said opening, said horn being substantially rectangular in cross-section and having two opposite walls stationary and diverging, the other two horn-walls being of similarly-flared shape but hinged at their inner ends, and means movable with each hinged wall for concealing any space between the forward edge of said wall and the adjacent side of said opening.

2. A cabinet having an opening at its front, a variable horn located therein and presenting its mouth toward said opening, said horn consisting of two opposite stationary walls and two walls hinged at their inner edges, and means for concealing any space between the forward edge of each hinged wall and the adjacent side of said opening.

3. A sound-conveyer or horn substantially rectangular in cross-section, having two opposite and diverging stationary walls, and having the other two walls of correspondingly-flared shape and slidingly hinged at their inner edges, in combination with means for moving the outer edges of said hinged walls in rectilinear direction, and means for producing a snug fit with the stationary walls in the different positions of adjustment.

4. A sound-conveyer or horn substantially rectangular in cross-section, having two opposite and diverging stationary walls, and having the other two walls of correspondingly-flared shape and slidingly hinged at their inner edges, in combination with means for moving the outer edges of said movable walls in rectilinear path.

5. A sound-conveyer consisting of a rectangular horizontally-opening throat and a horn substantially rectangular in cross-section, having two opposite stationary walls as continuations of the corresponding walls of said throat and the other two walls hinged

respectively at their inner ends to the corresponding walls of said throat, in combination with means for simultaneously moving the outer edges of said hinged walls toward or away from each other.

6. A sound-conveyer consisting of a rectangular horizontally-opening throat and a horn substantially rectangular in cross-section, having two opposite sides stationary and divergent as continuations of the corresponding walls of said throat, and having its other two sides of correspondingly-flared shape and hinged respectively at their inner ends to the corresponding walls of said throat.

7. A sound-conveyer or horn substantially rectangular in cross-section, and having two opposite sides stationary and divergent, and having the other two sides of correspondingly-flared shape and hinged at their inner edges so that their outer edges are movable.

8. The combination in a talking machine cabinet having an opening in one of its walls, a sound conveyer located in said cabinet and discharging toward said opening, a slideable closure member for said opening, and means comprising a portion of the sound conveyer wall connected to said closure member for varying the cross sectional area of the conveyer discharge as the closure member is moved.

9. The combination in a talking machine cabinet having an opening in one of its walls, a sound conveyer located therein and discharging toward said opening, of means normally closing the cabinet opening and adjustable to vary the area of said opening, and means operable by said means for varying the geometrical volume of said conveyer.

10. The combination in a talking machine cabinet having an opening in one of its walls, a sound conveyer located in said cabinet and discharging toward said opening, a pair of slideable doors for said opening, and means connected to the adjacent door edges for varying the geometrical volume of the conveyer as the doors are moved.

11. A sound conveyer comprising a conduit having at one end an opening for receiving sound and having a discharge, the area of which is variable by means of slideable mechanism, and means for varying the cross sectional area of said conduit from said discharge toward the sound-receiving end as the discharge area is varied by the movement of the said slideable mechanism.

In testimony whereof I have signed this specification.

GEORGE W. BEADLE.
